UNITED STATES PATENT OFFICE.

ARTHUR THOMPSON, OF TOLEDO, OHIO.

CLEANING-FLUID-INTRODUCING MEANS FOR ENGINE-CYLINDERS.

1,258,270.

Specification of Letters Patent. Patented Mar. 5, 1918.

Application filed April 11, 1917. Serial No. 161,348.

To all whom it may concern:

Be it known that I, ARTHUR THOMPSON, a citizen of the United States, and a resident of Toledo, in the county of Lucas and State 5 of Ohio, have invented a certain new and useful Cleaning-Fluid-Introducing Means for Engine-Cylinders; and I do hereby declare the following to be a full, clear, and exact description of the invention, such as 10 will enable others skilled in the art to which it appertains to make and use the same, reference being had to the accompanying drawings, and to the characters of reference marked thereon, which form a part of this 15 specification.

This invention relates to means for cleaning and removing carbon from the cylinders of internal combustion engines.

The primary object of my invention is the 20 provision of a simple device for containing a carbon cutting or softening liquid, such, for instance, as kerosene, and adapted to be easily and quickly attached to the priming cock of an engine cylinder in valve-controlled communication with its interior, whereby a quantity of such liquid is drawn 25 into the cylinder at each suction stroke of its piston.

The invention is fully described in the 30 following specification, and while, in its broader aspect, it is capable of embodiment in numerous forms, a preferred embodiment thereof is illustrated in the accompanying drawings, in which,—

Figure 1 is a side elevation of a device 35 embodying my invention in operative connection with an engine cylinder and having portions broken away. Fig. 2 is a perspective view of the priming cock engaging nipple and the means associated therewith for releasably connecting it to the priming cock, and Fig. 3 is a different perspective view of a portion of said connecting means.

Referring to the drawings, 1 designates 40 an engine cylinder and 2 the customary priming cock attached thereto, said cock having the cup portion 3 at its outer end which is connected to the body of the cock 50 by the reduced neck portion 4.

The device illustrated in the drawings 55 as embodying my invention comprises a receptacle 5, of cylinder form in the present instance, for containing kerosene or other cleaning liquid to be injected into the engine cylinder, and has a drain cock 6 tapped

into one end thereof and provided with a valve 7, whereby the passage therethrough may be opened or closed, as desired. The outer end of the cock 6 is threaded into a 60 nipple or nozzle part 8 which has its outer end preferably reduced in cross section and adapted to fit into the cup 3 of the priming cock 2. A collar 9 is mounted for longitudinal adjustment on the reduced outer 65 end portion of the nipple 8, being secured in adjusted position thereto by a set screw 10 and having its outer side faced with a gasket 11 to form a close, liquid-tight fit against the rim of the cup 3, as shown. 70 The nipple passage is enlarged at the rear of its discharge end to receive a check valve 12, in the present instance, of the ball type, which seats against the inner end of such enlargement to normally close the passage 75 therethrough, and is yieldingly held seated by a spring 13. A latch member 14 is pivotally connected to the nipple 8 for transverse swinging movements relative thereto and is adapted to swing into and out of en- 80 gagement with the neck portion 4 of the priming cock 2, being provided with a notch 15 in one end of its bottom portion for receiving said neck. When the nipple 8 has been placed with its outer end projecting 85 into the cup 3 and with its stop-shoulder or collar 9 resting on the rim of said cup, the catch member 14 is then swung from the dotted line position shown in Fig. 1 to the full line position, in which latter position 90 the catch member engages under the bottom edge of the cup 3 and draws the shoulder 9 closely to the cup rim. The catch member 14, in the present instance, has a finger piece 16 at one end and is provided at the sides of 95 its bottom cup engaging portion with upwardly projecting rims 17 which are pivoted to respective downwardly projecting arms of a U-shaped yoke member 18 which extends across the inner end of the nipple 8. 100 The yoke 18 has an opening 19 therein through which the outer end of the drain cock 6 projects and is intended to be firmly clamped to a shoulder or nut 20 on said drain cock by the nipple 8.

The cylinder 5 has its outer end provided with a removable cap or closure member 21 to facilitate a filling of the cylinder.

It has heretofore been the practice, in introducing kerosene or other carbon softening and cleaning liquid into the cylinders of an internal combustion engine, to intro-

duce such kerosene through the carbureter while the engine is running or to introduce such liquid separately into each cylinder through the customary priming cup or the 5 opening in which the spark plug is mounted when the engine is idle. The first of these methods is objectionable for the reason that the introducing of the kerosene simultaneously into all of the cylinders causes a choking 10 and frequent stopping of the engine, while the principal objection to the latter method is that the liquid cannot be introduced when the engine is running. With the use of my device it makes no difference 15 how fast a cleaning liquid is drawn into a cylinder with which connected, as the explosions taking place in the remaining cylinders of the engine will cause a continuous rapid running of the engine, so that there 20 is no danger of choking the engine. It is also found in practice that a more effective cleaning of an engine cylinder can be accomplished by the use of my device than by either of the methods above referred to or 25 by any other method of which I am aware.

I wish it understood that my invention is not limited to any specific construction, arrangement or form of the parts, as it is capable of numerous modifications without 30 departing from the spirit of the claims.

Having thus described my invention, what I claim as new and desire to secure by Letters Patent, is—

1. The combination with the cylinder of 35 an internal combustion engine and a priming cock attached thereto, said cock having a cup at its outer end, of a receptacle for a cleaning liquid having a drainage nipple adapted to removably seat on said cup, an 40 outwardly opening check valve disposed in

said nipple, and means carried by the nipple and operable to releasably engage the priming cock to retain the nipple in close engagement therewith.

2. The combination with the cylinder of 45 an internal combustion engine and a priming cock therefor, said cock having a cup at its outer end, of a receptacle for containing a cleaning liquid, a drainage cock extending from the lower end of said receptacle and having a nipple at its outer end for seating in the cup of said priming cock, an outwardly opening check valve in said nipple, and a catch member pivotally connected to said nipple and adapted to swing into 50 holding engagement with the under side of the priming cock cup to retain the nipple in engagement therewith.

3. The combination with the cylinder of 55 an internal combustion engine and a priming cock therefor, having a priming cup at its outer end, of a receptacle for a cleaning liquid, a valved drainage cock projecting from said receptacle, a nipple threaded on the outer end of said drainage cock and 60 adapted to project at its outer end into said priming cup, an adjustable stop-shoulder on said nipple for seating on the rim of the priming cup, an outwardly opening check valve in the passage formed by said drain 65 cock and nipple, and a catch member pivotally connected to said nipple for transverse swinging movements relative thereto and having its outer end portion shaped to swing under said priming cup and coöperate therewith to retain the nipple in close 70 engagement therewith.

In testimony whereof, I have hereunto signed my name to this specification.

ARTHUR THOMPSON.
